His Attorney.

UNITED STATES PATENT OFFICE

JOHN D. HILLIARD, OF SCHENECTADY, NEW YORK, ASSIGNOR TO GENERAL ELECTRIC COMPANY, A CORPORATION OF NEW YORK

SAFETY PRESSURE RELIEF AND INDICATING APPARATUS

Application filed June 10, 1928. Serial No. 369,903.

My invention relates to pressure relief apparatus for closed casings which are adapted to contain electrical apparatus and in which pressures may be produced through accident or otherwise sufficient to cause the rupturing of the casing. It is the object of my invention to provide an improved apparatus of this character including means for giving an indication when the apparatus has functioned. I have chosen to illustrate my invention as applied to an oil switch but it is to be understood that its use is not restricted to such for it is equally applicable to other forms of enclosed electrical apparatus, such, for example, as oil immersed transformers.

My invention will be better understood from the following description taken in connection with the accompanying drawing, and its scope will be pointed out in the appended claims.

Referring to the drawing, Fig. 1 is an exterior view of a portion only of an oil switch provided with a safety pressure relief device embodying my invention; Figs. 2 and 3 are cross-sectional views of the device taken at right angles to each other; and Fig. 4 illustrates a modification.

The contacts and operating mechanism therefor of the oil switch shown in Fig. 1 are arranged in a closed casing comprising the tank 1 to which is bolted the top 2 supporting the insulator bushings 3 and the mechanism housing 4. These casings are not hermetically sealed but in certain cases are provided with a discharge opening with which connects a cooling and separating device whereby the hot gas formed by the disintegration of the oil may be cooled and separated from oil carried along with it before it is discharged from the casing. In other cases the casing is constructed pressure-tight except for a small bleed hole through which the gas can gradually escape and the pressure inside and out become equalized. So long as the switch functions in the normal manner and is not required to interrupt circuits beyond its normal rating, a dangerously high pressure will not be developed within the casing but should an insulation break-down occur in the switch or should the operating mecha-

nism become deranged so that a sustained arc occurs in the casing a pressure may soon be developed in the casing sufficient to rupture it. In the copending application of William K. Rankin, Serial No. 204,687, filed July 11, 1927, and in my copending application, Serial No. 204,674, filed July 11, 1927, both assigned to the same assignee as the present application, there are disclosed and claimed safety relief devices of the nature of that shown herein and over which one feature of the present invention is an improvement.

The top 2 of the switch illustrated in Fig. 1 has an emergency relief opening of generous proportions surrounded by the integral upstanding flange 6. To this flange there is secured the end flange of the discharge pipe 7 which may lead directly to a point where hot gas and oil can do no harm or may connect with the header 8 common to a number of switches, which header leads preferably to such a point. Between the pipe 7 and the flange 6 and secured thereto by through-bolts is the safety pressure relief apparatus shown more clearly in Figs. 2 and 3. In the form illustrated it comprises the supporting member 11 having a circular opening therethrough into which extends the shallow annular flange 12. Clamped against opposite sides of this flange are the two concavo-convex diaphragms 14 and 15 which preferably are constructed of thin sheet metal, such, for example, as copper thoroughly annealed and having a spherical form. For the best results each diaphragm should make a snug fit in the opening of the supporting member and should make contact throughout its periphery with the side of the flange 12. The two diaphragms, as shown in Fig. 3, are arranged with their concave sides toward each other and are clamped against the flange 12 by the small central bolt 16. It is not necessary that the diaphragms make a gas-tight joint with the supporting member and the clamping means which I have shown forms a convenient means of quickly replacing new diaphragms for those blown out and does not interfere in the least with the free action of either diaphragm when an excess pressure on its convex face causes it to

collapse and to be blown bodily from the support. If the discharge pipe 7 exhausts independently of any other switch, a single diaphragm only, positioned with its convex face toward the switch is necessary but when 5 a plurality of switches discharge into a common receptacle or header, such as shown in Fig. 1, it becomes advisable to use a second diaphragm positioned with its convex face toward the header to prevent the first diaphragm from being blown out of position by 10 pressure which backs up the discharge pipe upon the discharge into the header of a companion switch. Inasmuch as the diaphragms of this relief device are entirely concealed 15 from view it is possible for the device to function without the switch attendant being aware of the fact. Since an operation of the device is probably the result of trouble 20 in the switch the operator should be immediately notified in order that the switch may be examined and also to replace the blownout diaphragms.

Between the two diaphragms, as shown in 25 Figs. 1 and 2, and extending across the opening in the support I have placed the frangible rod 18, for example, of glass, so as to be struck and carried away by the diaphragms when they are blown out. The rod may be supported in any suitable manner. To facilitate 30 its replacement I have shown by way of example the screw plug 19 having a recess for one end of the rod threaded into one side of the supporting member. At the opposite side of the member the rod is guided by 35 the screw 20 forming with the member a stuffing box. Attached to the supporting member I have shown the block 21 of insulation to which is secured the spring 22 bearing against the end of rod 18. Attached 40 also to the supporting member is another block 23 of insulation to which is attached the contact 24 which is positioned to be engaged by the spring 22 when the latter is not restrained by the rod 18. Any suitable 45 indicating device may be connected in circuit with members 22 and 24, such, for example, as the bell 25. If desired this circuit may also include suitable apparatus, not shown, for rendering the control circuit of the switch inoperative so as to prevent any closing of the switch if it is already open. As long as the diaphragms and frangible rod are in place 50 the contacts shown in Fig. 2 are held apart but as soon as the diaphragms are blown out, carrying away the rod with them, spring contact 22 closes the circuit and an alarm is given. Inasmuch as it is more desirable 55 that the bolt 16 be mounted at the center of the diaphragms than that the frangible rod should pass the center thereof, I preferably 60 arrange the holes for rod 16 at the centers of the diaphragms and slightly offset the rod 18 so as not to interfere with the tie bolt. It 65 is obvious that the contacts may if desired

be arranged to open instead of close the indicator circuit to cause the operation of the indicating device.

In the modified form of my invention illustrated by Fig. 4 the rod 18 is replaced by the wire 27 of easily broken conducting material, such, for example, as fuse metal. This wire preferably is supported in a tube 28 of frangible material, such as glass or hard rubber, where it passes the opening in the supporting member although it may, if desired, be left unsupported. In this arrangement the tie bolt 16 is offset with respect to the centers of the diaphragms. It is, of course, apparent that the tube 28 containing the easily broken wire 27 may be suitably offset with respect to the centers of the diaphragms, if desired, in the manner illustrated in Fig. 2 so that the tie bolt 16 may be mounted centrally of the diaphragm. The two ends of the wire are shown 75 attached to terminals 29 and 30 suitably secured by insulation to the supporting member 11. In circuit with the terminals 29 and 30 I have shown the winding of the relay 31 which is normally energized and which has 80 back contacts by which a second circuit is closed including the alarm bell 32. In accordance with this form of my invention current normally is flowing through the fuse and the relay winding. When the diaphragms blow 85 out the fuse is broken, opening the circuit and deenergizing the relay when the alarm bell is caused to operate.

What I claim as new and desire to secure by Letters Patent of the United States, is:

1. Electrical apparatus having a closed 100 casing provided with a safety discharge passage, diaphragm apparatus in said passage comprising a supporting member having an opening therethrough, a diaphragm normally closing said opening and adapted to be blown away by excessive pressure on one side thereof, and a frangible circuit-controlling member arranged in the path of movement of said diaphragm.

2. Electrical apparatus having a closed casing provided with a safety blow-out discharge passage, diaphragm apparatus in said passage comprising a supporting member having an opening therethrough, a blow-out diaphragm 115 normally closing said opening, and a frangible circuit-controlling member supported by said member in a position to be broken by the blowing-out of said diaphragm.

3. A closed casing adapted to contain electrical apparatus and having a safety discharge passage, a blow-out diaphragm apparatus in said passage comprising a supporting member having a circular opening therein and an internal flange, a concavo-convex 125 diaphragm in the opening with its concave side seated against said flange and a circuit-controlling frangible member supported by the member and arranged at the concave side of the diaphragm.

4. A closed casing containing electrical apparatus immersed in an insulating liquid, means connected with said casing forming a safety discharge passage for excessive pressure produced therein, blow-out diaphragm apparatus in said passage comprising a concavo-convex disk normally closing the passage and arranged with the convex side toward the casing, an alarm device, and a controlling member therefor arranged on the concave side of said diaphragm and adapted to be struck by the diaphragm when the same is blown out.
5. A safety blow-out diaphragm device comprising a supporting member having a discharge passage therethrough and an internal flange, a pair of concavo-convex diaphragms in said passage arranged with their concave faces toward each other, and a member engaging said diaphragms at their central portions for clamping the same against opposite sides of the flange.
6. A safety blow-out diaphragm device comprising a supporting member having a discharge passage therethrough and an internal flange, a pair of concavo-convex sheet metal diaphragms in said passage arranged with their concave faces toward each other, an adjustable rod engaging said diaphragms at their central portions for clamping the diaphragms against opposite sides of said flange and a circuit controlling member extending across said opening and arranged between said diaphragms.
7. Electrical apparatus comprising a closed casing provided with a safety blow-out discharge passage, a blow-out diaphragm normally closing said opening, said diaphragm adapted to be blown through said passage by predetermined pressure within said casing, and a circuit-controlling member operatively associated with said blow-out diaphragm and adapted to be actuated to cause a circuit-controlling operation in response to the blowing out of said diaphragm.

In witness whereof, I have hereto set my hand this sixth day of June, 1929.

JOHN D. HILLIARD.
